UNITED STATES PATENT OFFICE.

THEODORE F. MEINHARDT, GEORGE IRVING RAY, AND GILBERT G. RAY, OF CHARLOTTE, NORTH CAROLINA.

CLOSED HOT-AIR HEATING SYSTEM.

Application filed March 27, 1924. Serial No. 702,373.

To all whom it may concern:

Be it known that we, THEODORE F. MEINHARDT, GEORGE I. RAY, and GILBERT G. RAY, citizens of the United States, and residents 5 of Charlotte, in the county of Mecklenburg and State of North Carolina, have made certain new and useful Improvements in a Closed Hot-Air Heating System, of which the following is a specification.

Our present invention relates generally to 10 heating systems and more particularly to heating systems for dwellings and homes, our object being the provision of an arrangement constituting a closed hot air heating system which will do away with the disadvantages of the usual hot air systems, 15 wherein cold air is continuously taken into the same heated and delivered in a heated condition to the room or rooms where it is desired, and requiring, as it does, a large 20 furnace and the expenditure of a correspondingly large amount of coal or other fuel. According to our invention we propose the use of hot air in a closed system 25 and its delivery to the point of use within a closed radiator, the same air being heated over and over again in a furnace which is closed except for its communication with the circulating pipe or pipes to the radiator, 30 and which need be but a fraction of the size of the usual hot air furnace, with the resultant economy in the necessary fuel.

Our invention thus utilizes hot air in a system somewhat similar to a hot water 35 system, but without the disadvantages of handling the water and with a quicker and more constant circulation of greater efficiency.

In the accompanying drawing which illustrates 40 our present invention and forms a part of this specification:—

Figure 1 is a sectional view, more or less diagrammatic, illustrating the practical application of our system;

Figure 2 is a partial vertical longitudinal section on an enlarged scale through the radiator shown in Figure 1;

Figure 3 is a vertical longitudinal section through a slightly modified form of 50 radiator;

Figure 4 is an end view thereof, and,

Figure 5 is a partial horizontal section therethrough taken substantially on line 5—5 of Figure 3.

Referring now to these figures, and par-

ticularly to Figure 1, our invention contemplates the use of a furnace generally indicated at 10, having its fire pot 11 outletting through a flue 12 and having a vertical cylindrical drum 13 located between 60 and in spaced relation to the fire pot 11 and the outer wall of the furnace, the upper edge of which extends upwardly into a circulating flue 14 intended to afford both an upward passage for the heated air as indicated by the arrows 15, and a downward passage for the air from which the heat has been radiated as indicated by the arrows 16.

The extreme upper end of the flue 14, whose lower end thus communicates both 70 with the annular space 17 around the upright drum 13 and with the annular space 18 between this drum and the fire pot 11, opens into a vertical double pipe 19, and below its upper end this flue opens into the 75 lower end of a second vertical pipe 20, the latter providing for the upward passage of the heated air from the space 18 within the furnace to a radiator 21.

The lower end of the drum 13 is spaced 80 from the base of the furnace so that the annular spaces 17 and 18 are in communication at their lower ends, the air from which the heat has been radiated descending 85 through pipe 19 and along the lower portion of the circulating flue 14 to the space 17 from the lower end of which it passes into the space 18 where it is again heated by virtue of its close proximity to and around the fire pot 11 for subsequent passage upward along the upper portion of the flue 14, and through the radiator supply pipe 20 again to the radiator 21.

The radiator 21 may as shown in Fig. 1, be formed with a plurality of upstanding 95 hollow sections 22 spaced from one another, the lower ends of certain of which are in communication with the upper end of the supply pipe 20. These several sections of the radiator which is formed in its entirety 100 of light sheet metal, are in communication through short horizontal tubes 23. Moreover, the lower portions of certain of the sections of the radiator are in communication with the upper end of the outer pipe 19 so that when the heat has been radiated 105 from the air, the latter descends and thus a constant circulation is maintained of the same air which is continuously re-heated and re-used, thus avoiding the cooling effect 110

upon the furnace of the intake of cold air as in the usual hot air heating systems.

It is quite obvious that in view of the use of hot air in a closed system of this character we are able to utilize the radiators having thin walls, whereby the heat of the air therein may be quickly and effectively radiated into the space where it is desired and it is obvious that for the purposes of our invention a radiator such as indicated in Figures 3, 4 and 5 may be employed in lieu of that illustrated in Figures 1 and 2. The radiator of Figures 3, 4 and 5 contemplates the use of opposed headers 24 and 25 at the upper ends of the supply and outlet pipes 26 and 27, these headers being connected by upstanding spaced hollow sections or cross members 28 through which the air passes from the header 24 to the header 25.

Irrespective of the particular form of the radiator, however, it is obvious that our invention provides a hot air heating system which is superior to the usual hot air heating systems, which will be simple and durable, and which will also afford the advantages of high efficiency along with economy both in first cost and upkeep.

We claim:—

1. A closed hot air heating system includ-

ing a hot air furnace, an air circulating flue rising therefrom, a radiator having air supply and outlet pipes in communication with the said air circulating flue at spaced points in the length of the latter, and a drum in the air heating space of the furnace dividing the same into separate air spaces in communication with one another at the lower portion of the furnace, and in communication at their upper ends with the said air circulating flue.

2. A closed hot air heating system including a furnace, a jacket around the furnace, an air circulating flue rising from the jacket, a radiator having air supply and outlet connections in communication with the said air circulating flue at spaced points along the latter, and a drum around the furnace and within the jacket and forming separate air spaces in communication with one another at the lower portion of the furnace, a portion of the said drum extending into the said air circulating flue whereby to place the said air spaces separately in communication at their upper ends with the said air circulating flue.
